TUNED OSCILLATORY CIRCUIT

Siegfried Koch and Alfred Schmidt, Berlin, Germany, assignors to Telefunken Gesellschaft für Drahtlose Telegraphie m. b. H., Berlin, Zehlendorf, Germany, a corporation of Germany

Application May 17, 1941, Serial No. 393,860
In Germany March 15, 1940

7 Claims. (Cl. 178—44)

The invention relates to high frequency tuned oscillatory circuits comprising a casing and a condenser therein having a divided stator and a rotor supported by the cover and the bottom of the casing. With such oscillatory circuits it is necessary to change the rotor as soon as a frequency range between certain limits is attained. In consequence thereof every oscillatory circuit had empirically to be adjusted on a suitable frequency range, which only can be done by expensive work. To simplify said work and to save time it has already been proposed to provide a screw bolt in the wall of the casing of the oscillatory circuit and to adjust said screw against the condenser by longitudinal movement. In this way a variation of the mean wavelength of the oscillatory circuit can be effected, but at the same time the extension of the frequency range is influenced disadvantageously.

According to the invention the new oscillatory circuit is constructed in such a way that the mean wavelength and the extension of the range may be adjusted as far independently from one another as possible by varying the inductivity in order to change the mean length of the waves.

The characteristic feature of the invention, therefore, is to be seen in inserting into the air-space of a tuned oscillatory circuit of any known construction at a location where the inductivity is most effective (i. e., at a maximum current location) a metallic disc or the like adapted to be longitudinally moved along the axis of the circuit or to be shifted or rocked in order to vary the effect of the ring-shaped disc. Advantageously the disc comprises two halves adapted to be adjusted over against one another. The movement of the disc is effected by means of a gear mechanism to be rotated by a knob mounted on the casing of the oscillatory circuit.

A more detailed specification follows in conjunction with the drawing, in which

Fig. 1 is a cross section through the new oscillatory circuit, and

Fig. 2 is a longitudinal section.

The oscillatory circuit comprises a cylindrical casing 1 of metal having the cover 2 and a bottom 3. Bearings, not shown, are arranged in the centre of the bottom and the cover to support a shaft 5 for the rotor 6 cooperating with the stator comprising two parts, one of which is suitably made integral with the cover 2 and the other part with the bottom 3. Both parts are divided by the interstice 7 of different breadth as shown in Fig. 2.

Inside the casing 1 near the bottom 3 a circular disc 8 is arranged in such a way as to embrace the stator of the condenser or the inner tubular conductor of the oscillatory circuit. For this purpose the disc is provided with a central opening. The disc 8 may be moved longitudinally along the axis of the oscillatory circuit or may be displaced in any other suitable way. Advantageously the disc is manufactured of two parts hinged together by a pivot 9 in order to allow the parts to be tilted. Opposite the pivot 9 the end of each part 8 is provided with teeth 10 meshing with one another. The pivot 9 is supported by means of an insulated sleeve 11 arranged in a cap fastened to the wall of the casing 1. The toothed ends 10 of the ring-shaped disc 8 are provided with studs 12 and 13 respectively mounted in a bearing 14 arranged opposite the sleeve 11 in an aperture of the wall of the casing 1 and carried by a bridgepiece 16. Said bridge may be fastened to the casing by the intermediary of screw bolts 18 by which a removable cap 17 is mounted covering the aperture. The stud 13 is prolonged over the bridge and is provided with a slot for the insertion of a tool to adjust the position of the stud 13 the other end of which is keyed to the plate 8. The bearing 14 is provided with a clamping means for the purpose of locking the stud in the position adjusted by means of a screw 15.

To adjust the two parts of the ring-shaped disc 8 the cap 17 is to be removed and the stud 13 is rotated in such a way as to tilt the parts of the disc to vary its effect on the oscillatory circuit. The adjusted position of the disc 8 can be fixed by the clamping screw 15.

What we claim is:

1. A high frequency tuned oscillatory circuit comprising an outer conductor and an inner tubular conductor composed of two spaced elements to form a condenser, a disc permanently mounted between the inner and outer conductors, the center of said disc lying on the common axis of said outer and inner conductors, and means to a location near one end of one of said spaced elements for changing the position of a portion of said disc from the zone of maximum current to the zone of maximum voltage.

2. A high frequency tuned oscillatory circuit comprising an outer conductor and an inner conductor composed of two spaced coaxial elements, a condenser the stator of which is formed by the two elements of said inner conductor, a disc placed between the outer and inner conductors and comprising two parts hinged to one another,

the center of said disc lying on the common axis of said outer and inner conductors, and means connected with said hinged parts for changing the angular position of said two parts relative to each other.

3. A high frequency tuned oscillatory circuit comprising an outer conductor and an inner conductor comprised of two spaced capacitively coupled elements, a condenser the stator of which is formed by the two elements of the inner conductor, a ring-shaped disc placed between the outer and inner conductors and comprising two halves pivotally connected with one another and arranged in one position to be in the region of maximum current of said oscillatory circuit, the center of said disc lying on the common axis of said outer and inner conductors, and means for simultaneously varying the position of said parts from the zone of maximum current to the zone of maximum voltage.

4. A high frequency tuned oscillatory circuit comprising an outer and an inner conductor, a bottom connecting said conductors at the one end, a cover connecting the conductors at the other end, a circular disc having a central opening and consisting of two halves pivotally connected with one another and arranged near the bottom, the center of said disc lying on the common axis of the outer and inner conductors, and means adapted to adjust the said disc and to fix same in the position given.

5. A high frequency tuned oscillatory circuit comprising an outer and an inner conductor, a condenser the stator of which is formed by the inner conductor, a bottom and a cover connecting the ends of said conductors, and a ring-shaped disc placed near the bottom surrounding

the inner conductor and consisting of two halves hinged together by means of a pivot supported by the outer conductor, and gearing means for tilting the said halves about their common axis 5 of separation and for fixing same in the position given.

6. A high frequency tuned oscillator circuit comprising an outer conductor and an inner coaxial conductor, said inner conductor comprising two hollow spaced elements placed end to end on the same straight line, a rotatable element in the interiors of said two hollow spaced elements and capacitively coupled thereto to form a capacitor therewith, a disc located in the interior of said tuned circuit near the maximum current-minimum voltage end and having its center lying on the common axis of said outer and inner conductors, said disc being formed of two pivotally arranged parts, and means for changing the angular position of said parts of said disc relative to each other for bringing them into the zone of maximum voltage.

7. An oscillatory system comprising a shield, an adjustable capacity disposed within said shield and connected to said shield by means of inductances in the form of rods, said shield, inductances and capacity forming a resonant tank circuit and tuning means for said resonant tank circuit including two pivotally arranged parts angularly movable relative to each other and located between said shield and adjustable capacity, said pivotally arranged parts being mounted on one of said rods at a position of large current flow over said one rod.
